UNITED STATES PATENT OFFICE.

GEORGE C. VAN RODEN, OF PHILADELPHIA, PENNSYLVANIA, ASSIGNOR TO
J. E. CALDWELL & CO., OF SAME PLACE.

DESIGN FOR A BADGE.

SPECIFICATION forming part of Design No. 31,060, dated June 27, 1899.

Application filed May 29, 1899. Serial No. 718,754. Term of patent 14 years.

To all whom it may concern:

Be it known that I, GEORGE C. VAN RODEN, a citizen of the United States, residing in Philadelphia, Pennsylvania, have invented and produced a new and original Design for a Badge, of which the following is a specification.

My design for a badge is clearly illustrated in the accompanying drawing, the figure of 10 which represents a face view of the badge.

The essential feature of the design is the representation of a Greek cross, with segments of a circle extending from one arm of the cross to another, forming a backing for the 15 cross.

A is the cross, having a narrow border a, enclosing the field.

B are segments of a ring extending from one arm of the cross to another, and each one of these segments has a narrow border b on 20 the outside and a narrow border b' on the inner side. The fields of the cross and segments are in contrasting colors.

I claim—

The design for a badge as herein described 25 and as shown in the accompanying drawing.

In testimony whereof I have signed my name to this specification in the presence of two subscribing witnesses.

GEO. C. VAN RODEN.

Witnesses:

JOHN THIEL,
E. C. RHOADS.
